UNITED STATES PATENT OFFICE.

PHILIP MILLER, OF NORWICH, CONNECTICUT.

PRINTING-PRESS.

SPECIFICATION forming part of Letters Patent No. 249,969, dated November 22, 1881.

Application filed April 30, 1881. (Model.)

To all whom it may concern:

Be it known that I, PHILIP MILLER, a citizen of the United States, residing at Norwich, in the county of New London and State of Connecticut, have invented certain new and useful improvements in Printing-Presses known as "Drum Cylinder Presses;" and I do hereby declare that the following is a full, clear, and exact description of the invention, which will enable others skilled in the art to which it appertains to make and use the same.

My invention relates to that class of devices which are connected with a printing-press for the purpose of checking the momentum of the traveling table or bed as it reverses its motion. These devices are generally known as "air-bumpers."

My invention consists of an automatic tightening and relaxing gripe-lever, which operates the piston-rod of the air-bumper; also, of a continuous piston-rod with two heads working in two separate cylinders, which heads cushion or condense the air between themselves and one end of the cylinder, whichever way they are moved; also, of coiled springs arranged between a gripe operated sleeve and collars upon the piston-rod to break or lessen the concussion of the sleeve upon said collar before the air-cushions are operated; and, finally, in a sliding valve-stem working inside the hollow piston-rod, and serving to admit and then cut off the air from passage out of the cylinders.

In the drawings which form a part of this specification, like letters refer to like parts.

Figure 1 is a side view with part of frame removed. Fig. 2 is a plan view of the same. Fig. 3 is a sectional view on a line, *xx*, of Fig. 2. Fig. 4 is a detailed longitudinal section of the piston, the cylinders, and its heads, &c. Fig. 5 is a transverse section of the sleeve, piston-rod, and valve-stem, showing gripe *c*; and Fig. 6, a longitudinal vertical section of same.

A represents the type bed or table, to which a forward and backward motion is applied by connections from a wheel giving power.

B represent cams lying in the path of the bed, and serving to operate the elbow-shaped automatic gripes by elevating their free ends.

c c are the elbow-gripes for operating the piston-rods, and *d d* spring to keep the valve-stem in its correct position.

C is the part of the frame over which the bed moves.

C' is a freely-sliding friction-trough provided with friction-rollers, and moving between the frame *C* and the bed-plate *A*, as the latter reciprocates upon the former.

D is a power-wheel, to be operated by steam, water, or hand, as preferred.

e is a bent projecting arm, attached by bolts to the bed *A*, and serving to move the same.

f is a link-connection between *e* and an arm, *g*, moved by the power-wheel.

E E are the cylinder-heads, within which move the piston-heads *E' E'* when actuated by the hollow piston-rod *p'*.

h h are the friction-rollers at the ends of gripe bent levers *c c*.

j j are coils of wire, which first receive the impingement of the sleeve *p* when moved by the gripe-levers *c c*.

j' j' are collars secured to the hollow piston-rod *p'*.

K is the sliding valve-stem. *m* is the end opening in the same for admitting air, and *n* passages for the air into the cylinder upon either side of its head.

o is a screw connecting sleeve *p* to valve-stem *K*.

The operation of the above devices is as follows, viz: The type bed or table is moved backward and forward by the wheel *D* through the connections *g*, *f*, and *e*. The elbow gripe-levers are pivoted upon the table-frame, as seen in Fig. 1, and hence move backward and forward with it. Suppose the table to be moving to the right, as seen in Fig. 3 of drawings; then, shortly after movement commences, the friction-roller *h* on the outer free end of the left-hand elbow-gripe rides up the cam or incline *B*, and this, of course, while tilting the free end up, moves the lower end, provided with its rectangular opening, along the sleeve *p*, upon which it rides, until it catches so firmly upon the same as to carry it (the sleeve) along with it in its movement to the right. The lower ends of the gripe-levers have rectangular openings, which pass freely over the sleeve which operates the air-brake rod, except when the upper ends of said gripe-levers are raised by the cam-incline. Thus it will be seen that the movement of the table to the right auto-

matically operates left-hand gripe to take hold of the sleeve *p*, while the right-hand gripe slides by its rectangular opening freely over the said sleeve *p*. The forward movement of the sleeve is first taken up and checked or cushioned by the coil *j*, but finally moves forward the collar *j'*, attached to hollow piston-rod *p'*. The first part of the forward movement of the sleeve *p* carries forward the valve-stem *K*, being secured to the same by the screw *o*.

It will be seen that the same reciprocating piston-rod carries two heads, *E' E'*, which normally rest midway of the air-cylinders *E E*. During the movement to the right the piston-heads cushion against the outer end of right-hand cylinder and inner end of left-hand cylinder. During the motion of type-table to the left the cushioning (through the contained air, of course) is against inner end of right hand and outer end of left hand. Each movement, therefore, of the table is cushioned twice by the air in the opposite ends of cylinder and once by the coil-spring *j*. The same piston does double the work as in the old arrangement of a single cylinder and piston-head, and in the present instance the heads are at all times where no dirt or paper can collect about them. The present arrangement greatly avoids undue friction, which always causes a table to settle out of true line with both air-chambers and plunger-heads, and indirectly causes bad printing. When the movement of the bed is reversed the roller *h* on elbow gripe-lever drops off from incline *B*, and this at once releases the gripe of this lever upon sleeve *p*, so that the sleeve *p* passes through the rectangular slots in both grips by the recoil of the compressed spring.

It is perfectly evident that the cams *B* are to be arranged relatively to the length of the piston-rod so as to catch upon the sleeve *p* at the middle of the movement of the table, or nearer the last of said movement, according as a greater or less amount of so-called "cushioning" is desired.

It is evident that my devices can be used in any and all machines with reciprocating beds; and it is also evident that by doubling the collars a double-coil-spring bumper may be formed with same piston-rod, and that either single or double coil-spring bumpers may be used with the automatic gripe-levers without the use of air-cushions.

I am well aware that air-bumpers are not new, as applied to the reciprocating beds of printing-presses.

I am fully aware that air-cushions are common for printing-presses which operate to make a single (not a double) cushion at each

movement of the type bed or table, and that the piston of the air-cushion is operated by lugs or clamps—as, for example, the patents of C. B. Cottrell, Nos. 114,268 and 212,196; and I hereby disclaim all devices therein shown. 65

I am aware that in patents already granted the broad idea of a clamping-cam to grasp the piston-rod of an air-cushion or bumper is shown; but in such cases intermediate devices between the rod of the air-cushion and the bent lever are required. I do not therefore broadly claim this; but

What I claim as new and of my invention is—

1. In combination with the reciprocating bed of a printing-press, the angular pivoted lever *c c*, combined with an adjustable cam, *B*, to regulate the throw of the piston, the gripping end of said lever being slotted to form a rectangular opening, by which said end freely moves over the piston-rod of the double cylinder air-cushion, except when said lever is tilted so that the upper and lower sides of the slotted end firmly grasp and hold the said rod, all as and for the purposes described. 75

2. In an air-bumper of a printing-press, the combination of a single piston-rod with heads at each end working in air-cylinders closed at both ends, whereby at each movement of a reciprocating bed, by connecting mechanism, substantially as set forth, a double air-cushion 80 is produced, all as and for the purpose above set forth. 90

3. In combination with the two cylinders of a printing-press air-bumper and the single piston-rod with two heads, the valve-stem *K*, 95 open at each end, connected to the operating-sleeve *p*, and furnished with openings that admit air into the interior of the cylinders when openings in the piston-rod register with said valve-stem, all as and for the purposes described. 100

4. In combination with the two cylinders, the piston-rod with two heads, the sleeve *p*, operated by the automatic gripe-levers, and the wire coil-spring resting at one end against collars *j'* on the hollow piston-rod, and serving to partially break the force of the movement of the reciprocating table before the air-cushions commence to operate, all as and for the purposes set forth. 105

5. In combination with the two cylinders of the air-bumpers, their hollow double-headed piston-rod, and its sliding valve-stem carrying sleeve to the springs *d d*, to keep the sleeve *p* in a normally central position, all as and for 110 the purposes set forth. 115

PHILIP MILLER.
